UNITED STATES PATENT OFFICE.

JOHN M. GRIEST, OF CHICAGO, ILLINOIS, ASSIGNOR TO THE SINGER MANUFACTURING COMPANY OF NEW JERSEY.

SEWING-MACHINE RUFFLER.

SPECIFICATION forming part of Letters Patent No. 394,969, dated December 25, 1888.

Application filed December 27, 1887. Serial No. 259,094. (No model.)

To all whom it may concern:

Be it known that I, JOHN M. GRIEST, a citizen of the United States, residing at Chicago, in the county of Cook and State of Illinois, have invented certain new and useful Improvements in Sewing-Machine Rufflers, of which the following is a specification, reference being had therein to the accompanying drawings.

10 My invention relates to that class of ruffling or gathering attachments for sewing-machines which are operated from the needle-bar of the machine in such a manner that the ruffling-blade is advanced to make a gather as the needle rises and is retracted for a fresh hold on the goods as the needle descends to sew the gather, the object of my invention being to produce an attachment of the class referred to which will be simple in 15 construction, so that it may be made at little expense, and one in which the parts are so arranged that the power is applied to the best advantage, so that there will be but little drag on the needle-bar.

25 In carrying my invention into effect I provide a pendulous blade-carrying arm and pivot the same to a vertical standard, which is preferably formed integral with a presser-foot to be attached to the presser-bar of the 30 machine, as is common with these attachments. To an extension of the standard to which the blade-carrying arm is pivoted is also pivoted an operating-lever forked at its free end to embrace a screw or other 35 projection on the needle-bar, said operating-lever being connected by a link with the blade-carrying arm in such a manner that the said link and the rear portion of the said lever form a toggle. The link is provided 40 with a pin which projects into a slot in the blade-carrying arm, and a regulating-lever pivoted on and movable with the blade-carrying arm is provided with a lug which extends into said slot and against which the said pin 45 impinges to operate the blade-carrying arm. By adjusting the regulating-lever so that there will be more or less lost motion of the pin in the slot before it comes in contact with the lug of the regulating-lever the ruffling- 50 blade may be given any desired throw.

In the accompanying drawings, Figures 1 and 2 are elevations, with the parts in different positions, of my improved ruffler. Fig. 3 is a detail perspective view of the blade-carrying arm, the regulating-lever carried thereby, 55 and the ruffling-blade; and Fig. 4, a plan view of the attachment, partly in horizontal section, on line 4-4, Fig. 1.

The frame-work of the attachment comprises an ordinary presser-foot portion, A, 60 adapted to be attached to the presser-bar of a sewing-machine, and a standard, a, having an extension, a', an arm, a'', to which latter is secured the separator-plate b, being attached to or formed integral with the said extension. 65

The operating-lever C c, which is forked at its free end to embrace a screw or other projection in the needle-bar, is pivoted at its front end to the extension a' of the standard a, and to the said lever at d' (or rearward of 70 its fulcrum) is pivotally attached the link d, having at its free end the pin d'.

E is the pendulous blade-carrying arm or blade-carrier, pivoted at e to the standard a, and having a horizontal portion, e', at its lower 75 end, to which is attached the ruffling-blade e''. The arm E is provided with a slot, e'', which is entered by the pin d' on the link d, and to the said arm E is pivoted at f the regulating-lever F, having a lug, f', which enters the said slot e'' to be engaged by the said pin. The lever F is of spring metal, and is provided at its upper end with a lug, f'', to engage the toothed portion e' of the arm E, the said lug being normally sprung into engagement with the said toothed portion e'. The lever F is also provided with a finger-piece, f'', to be pressed against to release the lug f'' from engagement with the toothed portion e' of the arm E when the said lever is to 80 be adjusted. By adjusting the lever F to the left, Figs. 1, 2, and 3, the operative length of the slot e'' will be lessened, so that the throw of the ruffling-blade with a given movement of the operating-lever will be increased, and 85 by adjusting the said lever in the opposite direction or to the right, Figs. 1, 2, and 3, the operative length of the said slot e'' will be increased, so that the pin d' on the link d will have more or less lost motion in the said slot, 90 95 100

and a lesser throw will consequently be given to the arm E and the ruffling-blade carried thereby.

It will be observed that the front portion, 5 c, of the operating-lever and the link d form a toggle, and when the operating-lever is raised, as shown in Fig. 1, these two parts are in line with each other and the ruffling-blade is at its extreme forward position; but when 10 the operating-lever is depressed, as in Fig. 2, and the parts of the toggle are out of line the ruffling-blade is entirely retracted. As the needle-bar rises and raises the operating-lever, the toggle is gradually straightened out; 15 but as the parts approach the position shown in Fig. 1 the movement imparted to the blade-carrying arm becomes slower as the leverage of the toggle increases by the straightening out of the two parts of the toggle, so that at 20 the time when the strain or weight on the ruffling-blade is the heaviest (owing to the approach to completion of the gather being made) the leverage of the toggle is the greatest, and thus the strain or weight on the needle-bar will be equalized and the operation of 25 ruffling will be felt as little as possible by the machine.

To afford a compact arrangement of the parts, I prefer to provide the operating-lever 30 with offsets or bends at c⁴ c⁵ to give room for the link d and the blade-carrying arm E behind the said lever or between the latter and the standard a.

For convenience of description and to identify the arrangements of the parts or elements 35 of the blade-operating mechanism in the claims I will term the part of the ruffler or ruffler-frame at which the operating-lever is pivoted the "front" thereof (said part being 40 in front of the needle-bar and needle or on the side thereof toward the operator) and the presser-foot part of the ruffler (which is mainly behind the needle) the "rear part" or "end" thereof.

45 As above stated, the forked free end of the operating-lever receives a screw or other projection on the needle-bar of the machine, and as the body of the ruffler extends toward the operator in front of the needle-bar (the position of which relative to the ruffler is indicated by this forked end of the operating-lever) it will be evident that both parts of the toggle are in front of the needle-bar and needle. This arrangement of parts enables me 55 to connect the toggle with the ruffling-blade carrier in such a manner that the said carrier and the ruffling-blade will operate positively in both directions, and so that the toggle will be arranged to straighten out in forcing the 60 blade forward and to have its parts partly fold up when the blade is retracted, and thus the greatest leverage is secured at the times when there is the greatest strain or weight on the ruffling-blade, as hereinbefore described.

65 I am aware that it is not new, broadly, to operate ruffling-blades from the needle-bars

of sewing-machines by toggles; but the toggles heretofore used for this purpose have not been so arranged as to give the ruffling-blade its forward or ruffling stroke as the toggles 70 were straightened out, and thus the power has not been applied to the best advantage, as it is in my improved ruffler.

I claim—

1. In a sewing-machine ruffling attachment, 75 the combination, with the ruffler-frame, the ruffling-blade, and the carrier for the latter, of a toggle formed by an operating-lever and a link, said lever being pivoted at one end to the front end of said frame and the said link 80 being pivoted to said lever between the pivotal point and the free end of the latter, and being also connected to the said ruffler-carrier, whereby the said toggle is arranged to have its parts straighten out when the ruffling-blade is advanced and to fall out of line when the said blade is retracted, so that the leverage of the toggle is the greatest when the ruffling-blade is at its most advanced position and when most power is required, as set 85 forth.

2. In a ruffling attachment for sewing-machines, the combination, with the ruffler-frame, of a pendulous blade-carrier pivoted at its upper end to said frame and carrying 95 a ruffling-blade at its lower end, an operating-lever and a link, the latter being connected with said lever between its pivotal point and free end, and also with said blade-carrier, whereby said blade-carrier will be moved positively in both directions and the toggle formed by the operating-lever and link will be straightened out as the ruffling-blade is advanced to form a ruffle, thereby applying the 100 power to the best advantage.

3. In a sewing-machine ruffler, the combination, with the frame-work thereof having a standard, of a pendulous blade-carrying arm pivoted to the said standard, an operating-lever forked to embrace the needle-bar, 110 and a link pivotally attached to the said lever rearward of the fulcrum of the latter and also connected with said arm, the said link and the front portion of the said lever forming a toggle, to operate substantially as set 115 forth.

4. In a sewing-machine ruffler, the combination, with the ruffling-blade and its carrying-arm E, provided with a slot, of a toggle one part of which is provided with a pin extending into said slot to move the said carrying-arm positively in both directions, and means for operating said toggle from the needle-bar of the machine.

5. In a sewing-machine ruffler, the combination, with the standard a, of the pendulous blade-carrying arm E, pivoted to the said standard and provided with the slot e³ and the toothed portion e⁴, the regulating-lever F, pivoted to the arm E and having lugs e' e², 125 the operating-lever C c, and the link d, having the pin d².

6. In a sewing-machine ruffler, the combination, with the frame-work thereof, comprising the standard *a* and the pendulous blade-carrying arm arranged in front of the said standard, of the operating-lever pivoted to the front end of the ruffler and having the bends or offsets *c*⁴ *c*⁵, and the link *d* between the said lever and the said arm, as set forth.

In testimony whereof I affix my signature in presence of two witnesses.

JOHN M. GRIEST.
